UNITED STATES PATENT OFFICE.

JONAS R. FOSTER, OF STONEHAM, MASSACHUSETTS.

PENCIL-SHARPENER.

SPECIFICATION forming part of Letters Patent No. 402,914, dated May 7, 1889.

Application filed January 18, 1888. Serial No. 261,105. (No model.)

To all whom it may concern:

Be it known that I, JONAS R. FOSTER, of Stoneham, in the county of Middlesex and State of Massachusetts, have invented an Improvement in Pencil-Sharpener, of which the following description, in connection with the accompanying drawings, is a specification, like letters on the drawings representing like parts.

10 This invention has for its object to construct a pencil-sharpener adapted for giving a pencil when sharpened either a long or short point.

In accordance with this invention, a block provided with a recess and with a handle has 15 a blade secured to it, preferably in any adjustable manner, the cutting-edge of the blade lying adjacent to one wall of the recess. The blade has at its outer end a curved or hooked portion, one edge of which is sharpened to be 20 used to point the lead after the wood has been clipped or shaved off by the main portion of the blade.

Figure 1 shows an under side view of a pencil-sharpener embodying this invention, and 25 Fig. 2 a cross-section taken on the line *xx*.

The block *a* has a recess, *b*, formed in its under side. A blade, *c*, is secured to the block *a* above the recess *b*, the cutting-edge of said blade lying adjacent to the wall *b'* of the recess, and in a plane just beneath the under surface of the block *a*. The blade *c* is preferably attached to the block *a* adjustably; and to this end I provide the blade with transverse slots *c'*, through which are passed set-screws *c''*, which enter holes tapped in the block *a*.

The outer end of the blade *c* is curved or made hook shape, as at *c''*, and projects beyond the end of the block *a*, and is provided with 40 the cutting-edge *c'*. A handle, *d*, is fixed to the end of the block *a* opposite the hooked end *c''* of the blade. To sharpen a pencil, the

blade *c* is used to remove the wood and so much of the lead as desired, the tool being operated by the handle *d*, while the effect of 45 the blade *c* is like unto an ordinary shave.

When it is desired to point the pencil or produce a fine tapering point, the hooked blade or end *c''* is used like an ordinary blade. By the tool herein described the wood of the 50 pencil may be removed as much or little as desired and the point of the pencil exposed for any desired length, and also pointed to a nicety.

I may, if desired, omit the hooked end *c''*. 55

It will be seen that the blade may be readily removed and sharpened when desired and thereafter be replaced.

I claim—

1. A pencil-sharpener composed of the 60 block provided with a handle and with a recess in its under side, and a blade attached to the block above the recess and with its cutting-edge adjacent and parallel to one wall of the recess and beyond the under surface of 65 the block, substantially as and for the purposes set forth.

2. A pencil-sharpener composed of the recessed block *a*, the blade *c*, having the hooked end *c''*, and the handle *d*, all substantially as 70 and for the purposes set forth.

3. A pencil-sharpener composed of the block *a*, blade *c*, adjustably attached thereto, and the handle *d*, secured to one end of the said block, all substantially as and for the 75 purposes set forth.

In testimony whereof I have signed my name to this specification in the presence of two subscribing witnesses.

JONAS R. FOSTER.
